DRAPERY-SUPPORTING FIXTURE

Solomon Sheiber, Malden, Mass.

Application January 14, 1950, Serial No. 138,629

3 Claims. (Cl. 248—263)

1

This invention relates to improvements in fixtures for supporting drapes and provides an improved fixture for supporting a curtain that is provided with a valance.

The primary object of the invention is to provide a fixture of the class indicated which will be of efficient, simple and inexpensive construction and which can be quickly and readily secured in its operative position.

It is also an object of the invention to provide a fixture of the class indicated which can be secured in operative position either against a window frame or the like, or against any convenient flat surface disposed in proximity to a window or other opening in a wall of a building.

To these ends I have provided a fixture of the class indicated comprising a narrow elongated base member adapted to be secured flatwise in a vertical position against the flat surface of a window frame, or of a wall disposed in proximity to the window or other opening with which the drapery is to be associated, said base member being made with three outstanding relatively parallel horizontal arms. The three arms referred to comprise a pair of vertically aligned relatively long valance-supporting arms projecting perpendicularly from said base member adjacent to the outermost of its longitudinal sides, and a single outstanding relatively short curtain-supporting arm projecting perpendicularly from said base member inside of and opposite the lowermost arm of said pair. Two fixtures constructed as described are employed in connection with each window or other opening, one at each side thereof, each of said fixtures being a counterpart of the other so that their arms are adapted to jointly support three horizontal curtain rods or the like, viz., one rod for the curtain and the other two rods for the valance.

Other features of the invention are herein-after pointed out.

In the accompanying drawings—

Figure 1 is a side elevation of a drapery fixture constructed in accordance with this invention.

Figure 2 is a front elevation of the fixture shown in Figure 1.

Figure 3 is a sectional view taken horizontally through the wall of a building just above, and parallel with, the top of a window frame to which I have shown a pair of fixtures secured.

Figure 4 is a perspective view of an upper corner portion of a window frame having one of my improved fixtures secured thereto.

Figure 5 is a section on line 5—5 of Figure 2.

2

The base member 1 of the illustrated embodiment of the invention consists of a straight elongated length of rigid material characterized in that its exterior presents two adjoining flat side surfaces 2 and 3 (Fig. 5) disposed at right angles, the former being herein referred to as the inner side and the latter as the bottom side of the base member.

As herein shown this base member may be made from a strip of sheet metal bent longitudinally into angular form so as to provide the same with two flanges disposed at right angles to each other and including a side flange 4 and a bottom flange 5 whose exteriors provide the two flat surfaces 2 and 3.

Intermediate its opposite ends the bottom flange 5 is made with two longitudinally spaced-apart apertures 6, 6, for a purpose to be described later, while the side flange 4 is provided with a flat plate-like arm 7 projecting laterally and perpendicularly away from the free edge of flange 2 of base member 1 parallel with the bottom of flange 5.

The flat extension 7 is one arm of a right-angle bracket whose other arm 8 (Fig. 1) is fitted against the inner side of flange 4 and secured to said flange. When base member 1 and angular bracket 7—8 are made of metal as herein shown, they may be integrated by spot welding as indicated at 9, 9, in Fig. 1 of the drawings.

Adjacent to its upper end the base member 1 is provided with a relatively long outstanding horizontal arm 10 that is disposed in vertical alignment and paired with another outstanding horizontal arm 11 of the same length that is provided adjacent to the lower end of base member 1.

The arm 10 may be produced as part of a right-angle bracket made from standard metal strip stock provided with a short base portion 12 seated against the inner face of flange 5 of base member 1 and secured thereto by spot welding as indicated at 13, Fig. 2.

The arm 11 may conveniently be produced as part of a U-shaped bracket also made from standard metallic strip stock, the crotch or intermediate portion 14 being seated transversely against the inner face of flange 5 of base member 1 immediately adjacent to the lower end of the latter and secured to said flange by spot welding as indicated at 15 in Fig. 2 of the drawings. The other arm 16 of this U-shaped bracket is parallel with, but shorter than, the arm 11.

and is fitted snugly against the inner face of the flange 4 of base member 1.

The laterally projecting plate extension or arm 7 of flange 4 is formed with a pair of relatively parallel slots 17, 17, for the reception of screws or the like 18, 18, by means of which said extension or arm may, at times, be securely fixed in position against the outer face of a window frame 19, with the flange 4 of base member 1 held securely in position against one side of frame 19 as shown.

As shown in Fig. 2 the slots 17 are disposed perpendicularly to the flange 4 of the base member thus permitting the base member to be set and fixed in laterally adjusted position relatively to the side of the frame 19. This is important when the frame is constructed at its top with an outwardly projecting moulding (not shown) which usually extends beyond or around the side of the frame, since the lateral extension or arm 7 can then be fitted in position upon the outer face of the frame 19 with its upper edge against the lower edge of the moulding and with the flange 4 of base member 1 fitted against the end portion of the moulding which projects beyond the side of the frame 19 where it is held by means of the screws 18.

A counterpart of the fixture shown in Figs. 1, 2 and 4 is secured in position upon the window frame 19 at the opposite side thereof, the two fixtures then providing means for supporting three extension rods including a relatively short rod 20 for supporting the curtain and two relatively long extension rods 21 and 22 for supporting the valance. As usual, each rod may comprise two telescoping tubular sections that are longitudinally adjustable relatively to vary the length of the rod, with the opposite ends of each rod bent laterally at right angles to telescopically engage corresponding arms of the two fixtures as will be clear from Fig. 3, the opposite ends of the rod 20 being fitted upon the relatively short lower arms 16, 16, of the two fixtures; the opposite ends of the rod 21 being fitted upon the uppermost arms 10 of the two fixtures, and the opposite ends of the rod 22 being fitted upon the lowermost arms 11, 11, of the two fixtures.

The rod 20 occupies a position within a tubular pocket provided in the usual manner at the top of the curtain and indicated by broken lines at 23, while the two rods 21 and 22 occupy positions within tubular pockets provided in the usual manner at the top and bottom, respectively, of the valance, one of said tubular pockets being indicated by broken lines at 24 in Fig. 3.

When desired the base members 1 of the two fixtures 1 and 1A shown in Fig. 3 may be seated upon the face of the frame 19, or of the adjacent wall and fixed in either of those positions by means of the screws 18 driven through the apertures 6, 6, Fig. 2. When in either of these two

positions the extension arm or plate 7 is hidden behind the valance.

While I have herein shown each rod-supporting fixture as made up of a plurality of metal parts it will be clear to those skilled in the art that it may be molded in one piece from suitable moldable material such as a synthetic thermoplastic.

What I claim is:

1. A drapery fixture of the class described comprising a straight elongated base member having a flat longitudinal side surface; an arm extension projecting laterally and perpendicularly away from said flat side surface intermediate the opposite ends thereof so as to seat flatwise upon the outer surface of a window frame with said flat side surface fitted against one side of said frame, said arm extension being made with an aperture for the reception of a fastening element by which said arm is secured in position upon said frame, and three outstanding relatively parallel arms projecting perpendicularly from said base member including a pair of vertically aligned valance-supporting arms disposed in proximity to the opposite ends of the base member, respectively, and also adjacent to the outermost longitudinal side thereof, and also including a single curtain-supporting arm of less length than the arms of said pair and disposed adjacent to said flat side surface of the base member and in proximity to the lower end of the latter.

2. A drapery fixture according to claim 1 wherein said last-mentioned curtain-supporting arm is disposed laterally opposite the lowermost arm of said pair.

3. A drapery fixture of the class described comprising a straight elongated base member having a flat longitudinal side surface; an arm extension projecting laterally and perpendicularly away from said flat side surface intermediate the opposite ends thereof so as to seat flatwise upon the outer surface of a window frame, said arm extension being made with a pair of relatively parallel slots for the reception of fastening elements by which said arm is secured in position upon said frame, said slots being disposed perpendicularly relatively to said base member, and three outstanding relatively parallel arms projecting perpendicularly from said base member including a pair of vertically aligned valance-supporting arms disposed in proximity to the opposite ends of the base member, respectively, and also adjacent to the outermost longitudinal side thereof, and also including a single curtain-supporting arm of less length than the arms of said pair and disposed adjacent to said flat side surface of the base member and in proximity to the lower end of the latter.

SOLOMON SHEIBER.
